US0D1070672S

(12) **United States Design Patent** (10) **Patent No.:** **US D1,070,672 S**
(45) **Date of Patent:** **** Apr. 15, 2025**

(54) **AUTOMOTIVE GRILLE INSERTS**

(71) Applicant: **Vaughn Gittin, Jr. Motorsports LLC**,
Concord, NC (US)

(72) Inventors: **Lindsay Ross**, Los Angeles, CA (US);
Eric Bauer, Los Angeles, CA (US);
Mark Wagner, Harrisburg, NC (US)

(73) Assignee: **Vaughn Gittin, Jr. Motorsports LLC**,
Concord, NC (US)

(**) Term: **15 Years**

(21) Appl. No.: **29/858,350**

(22) Filed: **Oct. 31, 2022**

(51) **LOC (15) Cl.** **12-16**

(52) **U.S. Cl.**

USPC **D12/163**

CLAIM

The ornamental design for automotive grille inserts, as shown and described.

DESCRIPTION

FIG. 1 is a perspective view of automotive grille inserts, showing our new design;

FIG. 2 is a front elevation view thereof;

FIG. 3 is a back elevation view thereof;

FIG. 4 is a top plan view thereof;

FIG. 5 is a bottom plan view thereof;

FIG. 6 is a left elevation view thereof; and,

FIG. 7 is a right elevation view thereof.

The broken line showing in the drawings is included for the purpose of illustrating and forms no part of the claimed design.

1 Claim, 4 Drawing Sheets
